UNITED STATES PATENT OFFICE.

HEINDERICH FRIEDERICH WILHELM RITTER, OF SCHIEDAM, NETHERLANDS.

CONVEYING MEANS FOR BOTTLE-HOLDERS.

1,261,961.

Specification of Letters Patent. Patented Apr. 9, 1918.

Application filed March 1, 1918. Serial No. 219,922.

To all whom it may concern:

Be it known that I, HEINDERICH FRIEDERICH WILHELM RITTER, residing at Schiedam, the Netherlands, have invented certain 5 new and useful Improvements in Conveying Means for Bottle-Holders, of which the following is a specification.

In the manufacture of bottles the bottles, immediately after being blown are to be conveyed from the glass-oven to a cooling-oven. 10

At the present day this transport is accomplished in such a way that each bottle is placed in a suitable holder provided with a handle-bar and with a traveling-roller, after 15 which the holder is placed with its roller on a suitably inclined rail along which it moves under the influence of its own weight to the cooling-oven where the bottle is taken out; the empty holder then returns to the glass-oven along a rail having a reverse inclination. 20

These known conveying means have the objectionable feature not to provide sufficient allowance for the fact that the glass-blower is sometimes unable to place the holders with regular intervals on the rail leading to the cooling-oven. In blowing bottles numerous failures occur; now in case of such a failure the empty holders 25 turning from the cooling-oven, after being taken from the rail are to be thrown on the floor near the glass-oven as in such case the blower has not yet a new bottle ready to place same in the empty holder. Moreover, if some irregularity should occur at 30 the end of the conveyer near the cooling-oven a collision between the holders each carrying a hot bottle and arriving with short intervals is unavoidable, which may give 35 rise to the breakage of the glassware. 40

The present invention, which has for its object to avoid the above objectionable features, provides for an improvement in the construction of the lower end of said conveyers; the accompanying drawing is a 45 perspective view of an embodiment of said invention.

In the drawing, 1 is the suitably inclined rail made of angle iron secured to the top 50 flange of an angle iron 2, which in turn is supported by suitable brackets (not shown). The end of the rail has a shape which is somewhat like that of a strap; the said strap comprises a substantially circular bent-down 55 portion which at 3 extends laterally through a suitable distance, and ends in a substan-

tially vertical portion 4. At 5, that is to say about at the point where the circular end portion of the rail begins, a stop pin 6 or the like is provided comprising a horizontal 60 portion parallel with and preferably somewhat below the horizontal portion of the rail 1, and ending in a substantially vertical portion 10.

The bottle holder illustrated in the drawing 65 comprises a handle bar 7, a cup 8 for receiving a bottle and a traveling-roller 9.

Assuming now that an empty holder or a holder containing a bottle travels in its upright position along the rail 1, then the 70 handle bar 7 will near the end of the conveyer contact with the horizontal portion of the stop-pin 6, so that during its further movement along the bent-down circular portion of the rail it will gradually assume a 75 substantially horizontal position wherein it is supported both by the horizontal portion of the stop-pin 6 and by that of the rail 1. Owing to its momentum the holder in this 80 position will glide on for some time, until it comes to rest owing to the frictional resistance offered by its supports. The vertical portions 4 and 10 serve the purpose of preventing overrunning of the holder.

A process 11 of the holder prevents the 85 holder from shooting lengthwise off its support.

If the holder is supported in the position shown in the drawing, it can easily be taken off by hand; if, however, it should not yet 90 have been taken off the moment wherein the next holder arrives, then the latter, owing to the frictional resistance of the horizontal portions of the rail and of the stop-pin, will be braked so that when contacting with the 95 first holder its speed is reduced to a sufficient extent as to render the collision, if any, absolutely harmless. When the horizontal portions of the rail and of the stop-pin have some considerable length, they provide for a 100 suitable support to receive quite a number of bottle-holders disposed the one parallel with the other.

It is obvious that the distance between the stop-pin 6 and the horizontal portion of the 105 rail should suit the length of the bottle-holders for which the device is intended.

A great advantage of the described arrangement is the fact that it is inexpensive, and that it does not comprise any moving 110 part so that it is absolutely reliable in operation.

What I claim as my invention is:

1. In a conveyer for the transport of bottle-holders from a glass-oven to a cooling-oven and vice-versa, the combination of a substantially circular bent-down end portion of a rail, extending laterally through a suitable distance, with a stop-member which is provided substantially vertically below the point where the said circular rail portion begins and substantially parallel with and preferably extending at a level somewhat below that of the lateral portion of the rail.
2. In a conveyer for the transport of bottle-holders from a glass-oven to a cooling-oven and vice-versa of the type referred to, the combination of a substantially circular

bent-down end portion of a rail extending laterally through a suitable distance, with a stop-member which is provided substantially vertically below the point where the said circular rail portion begins and substantially parallel with and preferably extending at a level somewhat below that of the lateral portion of the rail, the said lateral portions of rail and stop-member ending in a positive stop.

In testimony whereof I have affixed my signature in presence of two witnesses.

REINERICH FRIEDERICH WILHELM RITTER.
